United States Patent Office

Des. 178,829
Patented Sept. 25, 1956

178,829

FIGURINE

Fred E. Crudele, Ashtabula, Ohio

Application April 17, 1956, Serial No. 41,100

Term of patent 14 years

(Cl. D29—23)

Fig. 2

Fig. 1

I claim:

The ornamental design for a figurine, as shown.
